POLYMERIZATION OF HYDROCARBON
GASES

Frederick W. Sullivan, Jr., and Robert F. Ruthruff, Hammond, Ind., assignors to Standard Oil Company, Chicago, Ill., a corporation of Indiana

Application November 25, 1931, Serial No. 577,228

13 Claims. (Cl. 196—9)

This invention relates to improvements in the polymerization of unsaturated gases and it pertains more particularly to a method for obtaining from petroleum oil and gases increased yields of gasoline of greatly improved characteristics.

We have discovered that when light olefins are polymerized in a continuous system in the presence of naphtha or a similar absorber oil at temperatures upwards of 900° F. and pressures upwards of 500 pounds per square inch, high yields of liquid products are obtained which contain large amounts of gasoline having an extraordinarily high knock rating.

Our invention should not be confused with the idea of circulating natural gases or refinery gases containing no olefins or only small proportions thereof with gas oil through pyrolytic cracking systems wherein the temperature and pressure conditions are dissimilar and wherein the effect of the gas is merely to obtain agitation or to repress gas formation by a mass action effect. Our invention deals with reactions under high pressures and with gases having relatively large olefin contents.

It appears that when the oil and the gas are brought together under such conditions a mutual activation and interaction takes place. It is possible that the oil, despite the fact that it would not under these conditions by itself show any large conversion to gasoline of higher antiknock value, is nevertheless in a sensitive or active state. Under these conditions the presence of the reactive olefins present in the gas is sufficient to bring about the conversion of the oil by combining with the constituents thereof which are sensitized or activated. We do not limit ourselves to any theory in our attempt to explain the phenomena; but it should be understood that our results cannot be explained on the basis of pyrolytic cracking.

The accompanying drawing illustrates diagrammatically (in the manner of a flow sheet) our improved polymerization system.

When our olefins are obtained from saturated hydrocarbon gases such as ethane, propane, butane, etc. the saturated gases are introduced through line 10 into heater 11 where they are heated at pressures up to 200 pounds per square inch and up to temperatures of from 1400 to 1600 degrees F. or thereabouts, following which they may be passed through a line 12 and soaking chamber 13 to effect further conversion. The soaking chamber may be cut out by closing valves 14 and 14', the gases then being passed through line 15 (by opening valves 16 and 16') directly

through cooler or exchanger 17. When cooled the gases pass through valve 18 and line 19 to compressor 20.

If a supply of olefin containing gases from some outside source is available these gases enter the system through line 21 and valve 21a. Light hydrocarbons from a stabilizing plant may be used directly or may be cracked as above stated. We may use gases from vapor phase oil cracking operations, which gases may have the following composition:

	Per cent
Methane and hydrogen	35.4
Ethylene	22.9
Ethane	13.3 15
Propylene	18.1
Propane	0
Butylenes	5.5
Butanes	1.4
Higher hydrocarbons	3.4 20

The gases from either or both sources are compressed in compressor 20 to 100-3000 pounds per square inch, after which the gases may take either of two courses. They may be cooled in cooler 22 and passed through line 23 to scrubber 24 where they are contacted with an absorber oil such as naphtha, or polymerized or hydrogenated hydrocarbons of equivalent boiling range; the absorber oil being introduced through line 25 by pump 26 which is supplied with fresh charging stock from line 27 or with recycled stock from line 28. Fuel gas containing primarily hydrogen and methane, but which may contain certain amounts of higher hydrocarbon gases, is eliminated from scrubber 24 through valve 25 take-off line 24a. The solvent charged with dissolved olefinic hydrocarbon gases is withdrawn from the scrubber by line 29 and is injected by pump 30 into the polymerization heater and reactor 31 which operates at temperatures of 900° 40 to 1200° F. and pressures of 750 to 3,000 pounds per square inch. Alternatively, the compressed olefinic gases may be introduced directly from compressor 20 into reactor 31 through pipe 32, in which case valve 28a is closed and valve 27a is 45 opened so that the absorber oil is introduced into the reactor by means of pump 30.

The reactor may be an elongated closed conduit such as a pipe still and it may also include an enlarged portion or reaction chamber to obtain the desired time of contact. This time may vary up to twenty minutes depending on reaction conditions; at temperatures of about 950° F. and pressures of about 800 pounds per square inch the optimum time of contact appears to be about

1½ to 2 minutes. The reaction products are removed through line 33, their pressure is reduced by valve 34, and they are then passed into fractionating tower 35. From this tower high boiling liquid products (higher than the gasoline boiling range) are removed by line 36 and they may either be eliminated through line 37 or returned through line 38, cooler 38' and pipe 28 back to the scrubber tower 24. Alternatively, valve 39 may be closed and all or part of the heavy polymerized oil from line 38 may be introduced through line 40 back to the reactor 31, so that the heavy stock may be subjected to further treatment in the presence of more olefin gases. Uncondensed gases and vapors of light products (gasoline, etc.) are removed from fractionating tower 35 by line 41 and the light products are condensed in cooler 42 and separated from uncondensed gases in separator 43. The separated light liquid products pass through line 44 to the stabilizer 45, which is provided with a suitable reboiling and fractionating means (not shown). Uncondensed gases are removed from separator 43 by line 46. These gases may be discarded through valve 46a or they may be recycled through pipe 47, recompressed, and reused. They may, on the other hand, be returned by pipe 49 to the inlet 10 of the gas cracking heater 11 whereby their olefin content will be increased prior to returning them to the scrubber and reaction system.

Finished gasoline is removed from stabilizer 45 through pipe 50 and uncondensed gases are removed therefrom through pipe 51. The uncondensed gases may be eliminated from the system through valve 51a or they may be passed through line 52 into line 10, and thence through the cracking and polymerization system. Alternatively, they may be passed through line 53 to line 19 and compressor 20 for recycling. The stabilizer gases withdrawn through line 51 and recycled with the aid of line 53 are intermediate in volatility between the gases removed from the top of separator 43 and the motor fuel withdrawn from the bottom of the stabilizer.

In order to bring out the remarkable results obtained by polymerizing olefins in the presence of naphtha, and the like, we will state the results of some of our work. In the following example one or two parts by weight of olefin gases were polymerized with one part absorber oil at a pressure of 800 pounds and a temperature of 950° F. in a continuous system. The liquid yield percentages are based on the amount by weight of liquid absorbing oil charged into the system.

A. When heavy naphtha with a knock rating of about 30 was treated for two minutes with gases containing 45% olefins, it yielded 125% liquids of which 91% was gasoline having a knock rating of 65.

It will be noted in the above example that we have obtained extremely high yields of liquid products. Furthermore, it will be noted that the gasoline obtained is characterized by an extremely high increase in anti-knock value.

Another extremely important feature of our invention is the fact that the polymerization reaction is readily controlled, i. e. there is no tendency for the temperature to "run away". The reaction appears to be in the vapor phase because of the presence of the relatively large amounts of gas present. The concentration of olefins should be as high as possible, and we have found that gases containing upwards of 25% olefins give excellent results.

The time of contact is important and if, for instance, in the above example the time is increased to 10 or 15 minutes the yield falls off rapidly and the knock rating of the gasoline is lowered. Shorter times of contact are relatively ineffective. 5

A particular feature of the invention is the use of a continuous system utilizing gases which are available in commercial quantities, and absorber oils which would otherwise require further pyrolytic cracking to render them suitable for high 10 antiknock motor fuels. By our process the naphtha feed stock or virgin naphtha is sensitized or activated in the presence of gases which evidently react with it to yield the high grade motor fuel, and the continuous feature makes it possible 15 to accurately regulate the heating and cooling rates, reaction periods, etc. on a commercial scale.

The term "absorber oil" as used in this specification and in the following claims is hereby defined to mean naphtha, gasoline, and/or hydro- 20 genated, cracked or polymerized hydrocarbons of approximately the same boiling range, the oil in any case having its characteristics changed by the polymerization reaction to produce an improved motor fuel of high knock rating. 25

While we have disclosed in detail preferred embodiment of our invention it should be understood that we do not limit ourselves to any of said details except as defined by the following claims which should be construed as broadly as the prior art 30 will permit.

We claim:

1. The method of producing gasoline of high knock rating from low knock rating naphtha and normally gaseous olefinic hydrocarbons which comprises scrubbing a compressed hydrocarbon gas mixture containing olefins with at least a part of said low knock rating naphtha so as to concentrate the olefin content thereof to at least 25% olefins, charging said concentrated olefinic gases 40 with said low knock rating naphtha to a reaction zone at a temperature of 950° to 1150° F. and a pressure of 750 to 3000 pounds per square inch for a period of time of about 1½ to 2 minutes, rectifying the converted material to obtain low boiling 45 uncondensed gases; high antiknock gasoline and a fraction of hydrocarbons intermediate in volatility between the low boiling uncondensed gases and the high anti-knock gasoline, and returning the said intermediate fraction of hydrocarbons 50 for reprocessing.

2. The method of producing gasoline of high knock rating from low knock rating virgin naphtha and normally gaseous olefinic hydrocarbons which comprises charging said low knock rating naphtha together with a compressed hydrocarbon gas mixture substantially free of hydrogen and methane containing at least 25% olefins to a reaction zone at a temperature of 900° to 1200° F. and a pressure of 800 to 3000 pounds per square 60 inch for a period of time sufficient to simultaneously convert the low knock rating naphtha and gaseous olefinic hydrocarbons into high knock rating gasoline, rectifying the total converted material to obtain low boiling uncondensed gases, 65 high knock rating gasoline and a fraction of hydrocarbons intermediate in volatility between the low boiling uncondensed gases and high knock rating gasoline, and returning the said intermediate fraction of hydrocarbons for reprocess- 70 ing.

3. The method of producing gasoline of high anti-knock rating from olefin-containing gases and naphtha which comprises charging low knock rating naphtha and concentrated olefin-contain-

ing gas substantially free of hydrogen and methane to a heating zone and heating same to a temperature of about 900° to 1200° F. while under a pressure of about 800 to 3000 pounds per square inch to effect a mutual activation and interaction of the olefins and naphtha, releasing the pressure on the reaction products and rectifying the converted material to obtain low boiling uncondensed gases, high knock rating gasoline and a fraction of hydrocarbons intermediate in volatility between the low boiling uncondensed gases and high knock rating gasoline, and returning the said intermediate fraction of hydrocarbons for reprocessing.

15 4. The method of producing gasoline of high anti-knock rating from naphtha and olefin-containing gases free of hydrogen and methane, which comprises charging a mixture of said gases and naphtha to a heating zone and heating the same to a temperature of 900-1100° F. while under a pressure of 750-2000 lbs. per square inch for a period of time sufficient to simultaneously convert the naphtha and olefin-containing gases into high knock rating gasoline fractionating the total converted material to obtain low boiling uncondensed gases, high knock rating gasoline and a fraction of hydrocarbons intermediate in volatility between the low boiling uncondensed gases and high knock rating gasoline, and returning the said intermediate fraction for reprocessing.

20 5. In the process of producing gasoline of high knock rating from low knock rating naphtha and normally gaseous olefinic hydrocarbons, the steps comprising compressing a hydrocarbon gas containing olefins to 100-3000 pounds per square inch, removing hydrogen and methane from said compressed gases to concentrate the olefine content thereof to at least 25% olefins, charging said concentrated olefinic gas with said low knock rating naphtha to a reaction zone maintained at a temperature between 900-1200° F. and under a pressure of 750 to 3000 pounds per square inch for a period of time sufficient to simultaneously convert the low knock rating naphtha and gaseous olefinic hydrocarbons into high knock rating gasoline, fractionating the total converted material to obtain low boiling uncondensed gases, high knock rating gasoline and a fraction of hydrocarbons intermediate in volatility between the low boiling uncondensed gases and high knock rating gasoline, and returning the said intermediate fraction of hydrocarbons for reprocessing.

25 6. In the process of producing gasoline of high knock rating from low knock rating naphtha and normally gaseous olefinic hydrocarbons, the steps comprising separating hydrogen and methane from a compressed hydrocarbon gas mixture containing olefins so as to concentrate the olefinic content thereof, charging said concentrated olefinic gases with said low knock rating naphtha to a reaction zone maintained at a temperature within the range of 900 to 1200° F. and to a pressure of 750 to 3000 pounds per square inch for a period of time sufficient to simultaneously convert the low knock rating naphtha and gaseous olefinic hydrocarbons into high knock rating gasoline, releasing the pressure on the reaction products and fractionating the converted material to obtain low boiling uncondensed gases, high knock rating gasoline and a fraction of hydrocarbons intermediate in volatility between the low boiling uncondensed gases and high knock rating gasoline, and returning the said intermediate fraction of hydrocarbons for reprocessing.

30 7. In the process of producing gasoline of high

knock rating from low knock rating naphtha and normally gaseous olefinic hydrocarbons, the steps comprising scrubbing a compressed hydrocarbon gas mixture containing olefins with at least a part of said low knock rating naphtha so as to concentrate the olefin content thereof to at least 25% olefins, charging said concentrated olefinic gases with said low knock rating naphtha to a reaction zone maintained at a temperature within the range of 900 to 1200° F. and under a pressure of 750 to 3000 lbs. per square inch for a period of time sufficient to simultaneously convert the low knock rating naphtha and gaseous olefinic hydrocarbons into high knock rating gasoline, rectifying the converted material to obtain low boiling uncondensed gases, high knock rating gasoline and a fraction of hydrocarbons intermediate in volatility between the low boiling uncondensed gases and high knock rating gasoline, and returning the said intermediate fraction of hydrocarbons to the scrubbing step for reprocessing.

35 8. A process of converting and stabilizing naphtha containing substantial quantities of hydrocarbons too unstable to be incorporated in motor fuels, which comprises subjecting the said naphtha to conversion conditions such that at least a portion of said hydrocarbons which are too unstable to be incorporated in motor fuels are converted to materials which are sufficiently stable to be incorporated in motor fuels while simultaneously reforming that portion of the said naphtha which was sufficiently stable originally to be incorporated in motor fuels, rectifying the total converted material to obtain low boiling uncondensed gases, motor fuel and a fraction intermediate in volatility between the low boiling uncondensed gases and motor fuel, and returning the said intermediate fraction for reprocessing.

40 9. A process for converting and stabilizing naphtha containing substantial quantities of hydrocarbons too unstable to be incorporated in motor fuels which comprises subjecting the said naphtha to conversion temperatures of 900 to 1150° F. whereby at least a portion of the said hydrocarbons which are too unstable to be incorporated in motor fuels are converted to materials which are sufficiently stable to be incorporated in motor fuels while simultaneously reforming that portion of the said naphtha which was sufficiently stable originally to be incorporated in motor fuels, rectifying the total converted material to obtain low boiling uncondensed gases, motor fuel and a fraction intermediate in volatility between the fixed gases and motor fuel, and returning the said intermediate fraction for reprocessing.

45 10. A process for converting and stabilizing a mixture of hydrocarbon materials, at least a substantial portion of which is sufficiently stable to be incorporated in motor fuel and a portion of which is of lower boiling range and too unstable to be incorporated in motor fuel, which comprises subjecting the said admixture to conversion conditions such that at least a portion of said hydrocarbons which are too unstable to be incorporated in motor fuels are converted to materials which are sufficiently stable to be incorporated in motor fuels while simultaneously reforming that portion of the said hydrocarbons which was sufficiently stable originally to be incorporated in motor fuels, rectifying the total converted material to obtain uncondensed gases, motor fuel and a fraction intermediate in volatility between the uncondensed gases and motor

fuel, and returning the said intermediate fraction for reprocessing.

11. A process for converting and stabilizing a mixture of hydrocarbon materials, at least a substantial portion of which is sufficiently stable to be incorporated in motor fuel and a portion of which is of lower boiling range and too unstable to be incorporated in motor fuels, which comprises subjecting the said admixture to conversion temperatures of between 900° F. to 1150° F. whereby at least a portion of the said hydrocarbons which are too unstable to be incorporated in motor fuels are converted to materials which are sufficiently stable to be incorporated in motor fuels while simultaneously reforming that portion of the said hydrocarbons which was sufficiently stable originally to be incorporated in motor fuels, rectifying the total converted material to obtain uncondensed gases, motor fuel and a fraction intermediate in volatility between the uncondensed gases and motor fuel, and returning the said intermediate fraction for reprocessing.

12. A process for converting and stabilizing a mixture of hydrocarbon materials, at least a substantial portion of which is sufficiently stable to be incorporated in motor fuel and a portion of which is of lower boiling range and too unstable to be incorporated in motor fuel, which comprises subjecting the said admixture to conversion temperatures and to a pressure between 750 pounds per square inch and 3000 pounds per square inch, whereby at least a portion of the said hydrocarbons which are too unstable to be incorporated in motor fuels are converted to materials which

are sufficiently stable to be incorporated in motor fuels, while simultaneously reforming that portion of the original material which was sufficiently stable originally to be incorporated in motor fuels, rectifying the total converted material to obtain uncondensed gases, motor fuel and a fraction intermediate in volatility between the uncondensed gases and motor fuel and returning the said intermediate fraction for reprocessing.

13. A process for converting and stabilizing a mixture of hydrocarbon materials, at least a substantial portion of which is sufficiently stable to be incorporated in motor fuel and a portion of which is of lower boiling range and too unstable to be incorporated in motor fuel, which comprises subjecting the said admixture to a temperature between 900° F. and 1150° F. and pressure between 750 pounds per square inch and 3000 pounds per square inch whereby at least a portion of the said hydrocarbons which are too unstable to be incorporated in motor fuels are converted to materials which are sufficiently stable to be incorporated in motor fuels while simultaneously reforming that portion of the said hydrocarbons which was sufficiently stable originally to be incorporated in motor fuels, rectifying the total converted material to obtain uncondensed gases, motor fuel and a fraction intermediate in volatility between the uncondensed gases and the motor fuel, and returning the said intermediate fraction for reprocessing.
